UNITED STATES PATENT OFFICE.

GEORGE CARR, OF CARRVILLE, IOWA.

FRAME FOR DOORS OR WINDOWS.

SPECIFICATION forming part of Letters Patent No. 706,157, dated August 5, 1902.

Application filed January 16, 1902. Serial No. 90,082. (No model.)

To all whom it may concern:

Be it known that I, GEORGE CARR, a citizen of the United States, residing at Carrville, in the county of Floyd and State of Iowa, have 5 invented a new and useful Improved Frame for Doors or Windows, of which the following is a specification.

This invention relates to improved frames for doors and windows especially adapted for 10 use in connection with frame houses.

The object of the invention is to provide as an article of manufacture a frame having building-paper disposed between the outer facing and the frame and extending out 15 from the frame some distance and adapted to lie against the building for preventing any air or moisture from entering between the joints formed at the juncture of the frame with the building.

20 Figure 1 of the accompanying drawings represents a perspective view of a window-frame having this improved protector applied thereto. Fig. 2 is a sectional view showing one side of a window-frame embodying my 25 improvements and a portion of a wall of a frame building in which the window-frame is fitted.

The same reference-numerals indicate corresponding parts in both the figures.

30 This improvement may be used in connection with either window or door frames and, as shown in the accompanying drawings, is embodied in a window-frame.

The window-frame 10 is of the usual construction, having the sill 11, stool 12, and the 35 groove 13 formed between them at the lower end thereof, having the usual outer facing 14, fastened to the jamb 15, which is provided with the ordinary slides 16 and 17 for the 40 windows. In Fig. 2 the frame is shown applied to a frame building having the usual weather-boarding 20, studding 21, lathing 22, and plaster 23. Between the outer casing or facing 14 and the jamb 15 is disposed 45 a wide strip of building-paper 30, which when the frame is applied extends over the studding 21, between it and the weather-boarding 20, and meets the adjacent edge of the paper 24, usually used over the sheathing 50 of a building for rendering it air and moisture proof. It will be readily seen that

the paper 24 may extend flush with the opening made in the building for the reception of the window-frame and the paper 30 lapped thereover between it and the weather-boarding, if desired; but this is not necessary to protect the joint. This strip 30 extends around the entire frame and affords a tight air and moisture proof joint. It is desired to construct the frames at the factory with 55 this paper strip disposed between the outer facing and the jamb so that they may be sold ready for application without any fastening devices being necessary for applying the strip to the building. 65

The sheathing of a house is usually covered with building-paper, which terminates at the edges of the door and window openings, so that when the frames are placed in position in the building air enters the building at the joint 70 thus formed, and if the frames be provided with a projecting wooden or metal flange or strip, which laps over the sheathing, the same objection is still applicable, as the air or moisture may still enter through the joint between 75 the flange and the sheathing. This invention is designed to avoid such entrance by providing a strip of building-paper fastened between two members of the window-frame and extending beyond the frame some distance and lying closely against the sheathing, between it and the weather-boarding, and meeting the adjacent edge of the paper usually used on the sheathing. If no paper is 80 used as a sheathing-covering, the paper projecting from the frame extends a sufficient distance to thoroughly protect the joint against 85 the entrance of both air and moisture.

I claim as my invention—

1. A frame for a building-opening, having 90 a strip as of paper surrounding, secured to and projecting outwardly beyond the frame, and a facing on the frame and bearing on the inner portion of the strip, the latter being secured between and projecting beyond the 95 frame and casing, to close the joints between the facing, the studding and the siding, substantially as described.

2. The combination with a building having 100 an opening therein, of a frame in said opening having a strip of paper fastened between two of its members and extending outwardly

therefrom and adapted to lie against the face of said building, said strip extending around and encircling said frame and projecting beyond the latter, and siding bearing on said 5 projecting portion of the strip, the latter closing the joints between the facing, the studing and the siding.

In testimony that I claim the foregoing as my own I have hereto affixed my signature in the presence of two witnesses.

GEORGE CARR.
